BLOCKING DEVICE FOR OPHTHALMIC LENSES

James F. McCarthy, Oaks Corners, N. Y., assignor
to Shuron Optical Company, Inc., Geneva,
N. Y., a corporation of New York

Application November 19, 1949, Serial No. 6,159

Term of patent 14 years

(Cl. D57—1)

To all whom it may concern:

Be it known that I, James F. McCarthy, a citizen of the United States of America and resident of the village of Oaks Corners, in the county of Ontario and State of New York, have invented a new, original, and ornamental Design for a Blocking Device for Ophthalmic Lenses, of which the following is a specification, reference being had to the accompanying drawing, forming part thereof.

In the drawing:

Figure 1 is a front perspective of a blocking device for ophthalmic lenses, showing my new design; and

Figure 2 is a rear elevational view thereof.

I claim:

The ornamental design for a blocking device for ophthalmic lenses, substantially as shown.

JAMES F. McCARTHY.
